DESIGN FOR A GUARD FOR SEWING MACHINES

Alexandra P. Duba, San Francisco, Calif.

Application March 21, 1945, Serial No. 118,615

Term of patent 7 years

(CL. D70—2)

To all whom it may concern:

Be it known that I, Alexandra P. Duba, a citizen of the United States, residing at 280 Edgehill Way, San Francisco, California, have invented a new, original, and ornamental Design for a Guard for Sewing Machines, of which the following is a specification, reference being had to the accompanying drawing, forming part thereof, in which

Fig. 1 is a plan view of the guard for sewing machines showing my new design;

Fig. 2 is a side view of the same;

Fig. 3 is another side view of the same;
Fig. 4 is a front perspective view of the guard for sewing machines shown in Fig. 1; and
Fig. 5 is a back perspective view of the guard for sewing machines shown in Fig. 1.

I claim:

The ornamental design for a guard for sewing machines, as shown.

ALEXANDRA P. DUBA.
